US00D934853S

(12) **United States Design Patent** (10) **Patent No.:** **US D934,853 S**
(45) **Date of Patent:** **** Nov. 2, 2021**

(54) **DEVICE**

(71) Applicant: **ZooBean LLC**, Wilmington, DE (US)

(72) Inventors: **Felix Lloyd**, Washington, DC (US);
Jordan Bookey, Washington, DC (US)

(73) Assignee: **ZOOBEAN LLC**, Wilmington, DE
(US)

(**) Term: **15 Years**

(21) Appl. No.: **29/773,975**

(22) Filed: **Mar. 12, 2021**

Related U.S. Application Data

(63) Continuation of application No. 29/678,015, filed on Jan. 25, 2019, now Pat. No. Des. 913,279.

(57) **CLAIM**

The ornamental design for a device, as shown and described.

DESCRIPTION

FIG. 1 is a top, front, left-side perspective view of a device in accordance with our new design;

FIG. 2 is a front elevational view thereof;

FIG. 3 is a rear elevational view thereof;

FIG. 4 is a right-side elevational view thereof;

FIG. 5 is a left-side elevational view thereof;

FIG. 6 is a top plan view thereof; and,

FIG. 7 is a bottom plan view thereof.

The broken lines immediately adjacent the shaded areas represent the bounds of the claimed design while all other broken lines are directed to unclaimed portions; the broken lines form no part of the claimed design.

1 Claim, 6 Drawing Sheets
